D. A. PORTERFIELD, OF NEW PARIS, OHIO.

Letters Patent No. 84,759, dated December 8, 1868.

IMPROVEMENT IN WASH-BOILERS.

The Schedule referred to in these Letters Patent and making part of the same.

To all whom it may concern:

Be it known that I, D. A. PORTERFIELD, of New Paris, in the county of Preble, and State of Ohio, have invented a new and useful Improvement in Wash-Boilers; and I do hereby declare that the following is a full and exact description thereof, reference being had to the accompanying drawing, making a part of this specification, in which—

Figure 1 is a view of the boiler, with a section removed, showing the interior.

Figure 2 is the lid.

Figures 3 and 4 are spouts.

The same letters in the different figures refer to corresponding parts of the boiler.

My invention relates to an improvement in wash-boilers, in which the boiling water is spouted above its level in the boiler, and pours back in streams, thus producing a thorough circulation of the water in the boiler, resulting in a rapid cleansing of the clothes by the boiling-process.

To enable others skilled in the art to make and use my invention, I will proceed to describe the same with reference to the drawings.

A represents an ordinary wash-boiler.

C and C' are spouts, (constructed of tin or other sheet-metal,) with their bases resting on the bottom of the boiler.

The spouts C and C' are sufficient in size at their bases to maintain them in an upright position, and taper to the top, where they terminate in small tubes.

The peculiar shape of the spouts is designed to require the least amount of room in the boiler, the portion or side adjacent to the end of the boiler being rounded to conform in shape to said end.

The inner side of the spout is flat and curved, by which a considerable size of base is obtained without materially detracting from the ordinary capacity of the boiler.

The result of constructing the spouts as described, with their bases considerably larger than their tops, is a continuous flow of water, when boiling, either with or without a cover on the boiler; and the peculiar shape of the spouts, as shown, also causes a partial vacuum within the base when the boiler is in operation, by which said spouts are held firmly in their positions.

When the boiler is constructed with a drop-pit, the bottom edges of spouts may be made uniform, as the depression in the boiler allows the water to flow beneath the spouts, but when the bottom of the boiler is flat, a sufficient space must be provided for admitting the water, as shown at e, fig. 3.

d and d' are valves in the boiler-lid, by which the steam is allowed to escape, thus preventing the water from boiling over the sides of the boiler, without the necessity of removing the lid.

Having thus fully described my said invention, What I claim, and desire to secure by Letters Patent, is—

In combination with the boiler, the conical or pyramidal spouts, as described, i. e., their bases resting in the bottom of the boiler, without the intervention of a horizontal partition, and so arranged, as to admit the supply of water by spanning the sunken pit, or by means of an opening at the bottom, as set forth.

D. A. PORTERFIELD.
